CLAIM

The ornamental design for a luminaire component, as shown and described.

DESCRIPTION

FIG. 1 shows a bottom perspective view of the luminaire component.

FIG. 2 shows a top perspective view of the luminaire component shown in FIG. 1.

FIG. 3 shows a top perspective view of the luminaire component shown in FIGS. 1 and 2 in isolation.

FIG. 4 shows a front view of the luminaire component shown in FIG. 3, the back view, right side view, and left side view being mirror images of the front view.

FIG. 5 shows a top plan view of the luminaire component shown in FIG. 3; and,

FIG. 6 shows a bottom plan view of the luminaire component shown in FIG. 3.

Portions or features of the luminaire component not shown in the drawings form no part of the claimed design. Portions or features of the luminaire component shown in broken lines form no part of the claimed design.

1 Claim, 5 Drawing Sheets
